UNITED STATES PATENT OFFICE.

JAMES H. PEARSON, OF BLOOMFIELD, INDIANA.

FACING-BLOCK.

No. 880,092.

Specification of Letters Patent.

Patented Feb. 25, 1908.

Application filed May 31, 1907. Serial No. 376,520.

To all whom it may concern:

Be it known that I, JAMES H. PEARSON, citizen of the United States, residing at Bloomfield, in the county of Greene and State of Indiana, have invented certain new and useful Improvements in Facing-Blocks, of which the following is a specification.

The present invention relates to an improved facing block or tile which may be employed either for exterior or interior work, and which embodies novel means for producing a secure interlocking connection with the cement or concrete backing to which the block is applied.

The primary object of the invention is to provide a block of this character formed with cement receiving sockets which are so designed and arranged as to enable the cement to readily enter the same and form a secure joint for retaining the block in position.

For a full description of the invention and the merits thereof and also to acquire a knowledge of the details of construction and the means for effecting the result, reference is to be had to the following description and accompanying drawings, in which:

Figure 1 is a perspective view showing a facing block embodying the invention. Fig. 2 is a back plan view of one of the facing blocks. Fig. 3 is a transverse sectional view on the line 3—3 of Fig. 2. Fig. 4 is a similar view on the line 4—4 of Fig. 2.

Corresponding and like parts are referred to in the following description and indicated in all the views of the drawings by the same reference characters.

A facing block embodying the present invention comprises a body portion 1 which may be of any desired outline or configuration and may be formed of any suitable material such as glass, porcelain or the like. In the present instance the facing block is shown as rectangular in shape and is provided in its rear face with a plurality of sockets 2 designed to receive the cement or concrete backing to which the facing block is applied. These sockets 2 are arranged in a plurality of groups or rows and have their axes inclined to the face of the block, the axes of each group being inclined in a different direction from those of the next adjacent group whereby after the facing block has been placed in position and the cement has hardened or set,

the said block is held rigidly in position and can not be removed or displaced without breakage. Attention is also directed to the fact that these sockets 2 are flared outwardly, the mouths of the same having a greater diameter than the bases, such construction enabling the cores to be readily removed when manufacturing the block, and also facilitating the entrance of the cement backing into the sockets. As shown on the drawing the sockets 2 are arranged in a plurality of transverse rows, the sockets of each row being arranged alternately with respect to the sockets of the next adjacent row and being inclined in an opposite direction as will be readily apparent from an inspection of Figs. 3 and 4 which are sectional views through the sockets of two adjacent rows. In applying the facing block the rear face of the same is pressed against the green cement backing until the cement which is in a plastic condition enters and completely fills all of the sockets. It will then be apparent that after the cement has hardened the facing block will be securely bonded in position and can not be removed or displaced without breakage.

Having thus described the invention, what is claimed as new is:

1. A facing block comprising a body portion having a plurality of circular sockets formed therein, the said circular sockets being arranged in rows and the sockets of each row being disposed alternately with respect to those of the next adjacent row while the sockets of the various rows are inclined in opposite directions.

2. In a facing block comprising a body portion having a plurality of sockets formed therein which are flared outwardly, the mouths thereof being of a greater diameter than the bases, the said sockets being arranged in rows and the sockets of each row being disposed alternately with respect to those of the next adjacent row, the sockets of the various rows being inclined in opposite directions.

In testimony whereof I affix my signature in presence of two witnesses.

JAMES H. PEARSON. [L. s.]
